Primary Examiner—Marcus A. Jackson**[57] CLAIM**

The ornamental design for a light for a remote control device, as shown and described.

DESCRIPTION

FIG. 1 is a left side elevational view of a light for a remote control device showing my new design, with the opposite side being a mirror image, and with the broken line showing for illustrative purposes only and forming no part of the claimed design;

FIG. 2 is a front view;

FIG. 3 is a back view;

FIG. 4 is a top view; and,

FIG. 5 is a bottom view.
